UNITED STATES PATENT OFFICE.

SIGVARD SIMONSON, OF HAMMOND, INDIANA.

DRAFT KEY.

Application filed December 12, 1925. Serial No. 74,964.

The invention relates to draft keys for connecting a coupler butt with the draft rigging of a railroad car.

The primary object of the invention, generally stated, is to provide a draft key designed to replace the ordinary type of key for taking up wear and restoring the relatively movable parts to normal position.

It is well known that after prolonged use railroad car couplers become upset or shortened by impact, resulting in decrease in clearance between coupler horn and the buffing face of the striking casting, this, in turn, cutting down the normal draft gear travel and reducing the efficiency thereof. It is quite clear that damage to the car and lading will be the inevitable result of this condition. The present method of remedying this is to apply a new coupler.

It is with the above facts in view that I have designed the present invention which has for a more specific object the provision of a draft key of such formation that when engaged through the slots in the cheek plates and coupler shank it will operate to move the coupler forwardly to such an extent that the distance between the coupler horn and striking casting will be normal, thereby relieving or preventing undue strain upon any of the parts of the car structure, it being consequently possible to use a coupler for a much greater length of time than is ordinarily possible, this feature resulting in a material saving in the upkeep.

A further object of the invention is to provide a draft key which is capable of use not only in connection with the coupler shank but also in association with the follower engaged thereby, in certain types of draft rigging, the key being readily interchangeable with and consequently adapted to replace a key of the ordinary type.

A still more specific object is the provision of a key formed of a plurality of sections and having means for preventing relative movement of the sections when installed and in service, the key being, moreover, of such shape and construction as to advance the coupler, or the follower therefor, to compensate for the decrease in the distance between the horn and buffing face, it being then possible to insert shims or the like rearwardly of the coupler or follower to restore the draft gear travel to standard length.

Another object of the invention is to pro-

vide a draft key which may be used without necessitating any alterations whatsoever in the already existing parts and which may be installed in a simple manner.

To the attainment of the foregoing and other objects and advantages, the invention may consist in the arrangement and combination of parts and the structural features to be hereinafter more fully described and claimed and illustrated in the accompanying drawings in which:

Figure 1 is a horizontal section through a draft gear, or portion thereof, showing a pair of the keys in use, a portion of the coupler and the keys themselves being shown in plan,

Figure 2 is a vertical longitudinal section, the coupler and follower therefor being shown in side elevation, and

Figure 3 is an end elevation of one of the keys showing the stop and retaining means thereon.

Referring to the drawings in detail, the numeral 1 designates the center sills of a railroad car secured at their ends to a striking casting 2 having the usual buffing face 3. The center sills are slotted in the usual manner for the accommodation of the cheek plates 4 which are secured thereto and which are formed with elongated slots 5 and 6. The yoke 7 is located between the center sills and is provided with slots 8 and 9 which register to a greater or less extent with the slots 5 and 6 respectively in the cheek plates. The coupler is indicated generally by the numeral 10 and includes a shank 11 located between the arms of the yoke, this shank being slotted at 12 as is customary for the accommodation of the usual draft key, not shown, which also extends through the slots 5 and 8 in the cheek plates and yoke arms respectively. The coupler is provided with the usual horn 13 which should be spaced a certain standard distance from the buffing face 3. In the particular draft rigging illustrated, there is shown a follower 14 which cooperates with the butt of the coupler shank and with whatever specific gear is provided, the draft gear not being illustrated as unnecessary to a proper understanding of the invention.

This follower is slotted at 15 for the passage of a second draft key which also passes through the slots 6 and 9 in the cheek plates and yoke arms respectively. In devices of this character, it is known that after pro-

longed use the slots in the coupler may become elongated and the butt may become upset or battered and consequently shortened so that when the parts are in a supposedly natural position there is really a decrease in the distance between the horn and the buffing face so that the draft gear does not have its full travel before the horn strikes the buffing face. Under ordinary circumstances it has been a common practice, when this occurs, to remove and discard the coupler and replace it with a new one, the cost of such installation being, of course, high.

In carrying out the present invention I provide substantially similar replacement keys designated generally by the numerals 16 and 16^a the essential feature being the formation or provision of a forward offset where the key passes through the slot in the coupler shank or in the follower, as the case may be. Obviously, it would not be practicable to insert such a key if it were made as one integral body, for which reason I have shown it as formed of sections 17, 18 and 19 adapted to be successively inserted through the slots in the cheek plates, yoke arms and the coupler shank or follower and to be subsequently connected whereby to prevent withdrawal or displacement. The section 17 is represented as formed with a forward extension 20 while the section 19 is shown as formed with a corresponding depression or recess 21. It is intended that the distance between the edge of the recessed portion 21 and the edge of the extension 20 be substantially the same as the width of the end portions of the key, this distance furthermore corresponding to the width of the ordinary key to be replaced. The confronting edges 22 and 23 of the sections 17 and 19 are represented as straight or plane and preferably parallel, and the section 18 fits between them.

For preventing longitudinal movement of the assembled key, use may be made of collars 24 arranged in embracing relation thereto, the outer edges of the sections 17 and 19 being preferably grooved at 25 for the reception of the collars. Relative movement of the sections is prevented as by means of pins 26 of staple-like form, these pins having their arms 27 engaging within mating notches 28 in the confronting edges of the sections 17, 18 and 19, the ends of the arms being upset, as indicated at 29, to prevent withdrawal.

Assuming that the coupler butt and the rear end of the slot have become battered so that the travel of the draft gear is decreased, instead of replacing the coupler, I withdraw or remove the ordinary keys which engage the coupler and the follower and which connect them with the remainder of the draft rigging. The sections 17 and 19 of the rear or follower engaging replacement key 16^a

are then inserted through the slots 6, 9 and 15 and moved apart to bring the extension 20 and recessed portion 21 into engagement with the opposite ends of the slot 15. This results in advancing the follower and the latter, being in engagement with the coupler butt, moves the coupler forwardly. When the sections 17 and 19 are first inserted, the collars 24 are engaged thereon prior to the separating of the sections so that the grooves 25 will receive or engage the collars. The intermediate section 18 is then slid into place between the sections 17 and 19, the parts being so positioned that the notches 28 will register or mate. The securing members 26 are then inserted through these registering notches and the ends thereof upset, as shown, to prevent withdrawal.

The forward key 16 is then placed in position, the sections 17 and 19 being inserted first, the former bearing snugly against the forward ends of the slots 8 in the yoke arms. The forwardly offset portion 20 of the section 17 is accommodated within the forward end of the slot 12 which has become elongated as the result of wear. The recessed portion 21 of the section 19 bears snugly against the rear end of the slot 12. Quite naturally, this close or tight engagement at the points mentioned is not accomplished until the sections 17 and 19 have been forced apart and the section 18 inserted between them. The detailed operation of placing the forward key in position and locking the sections thereof together is identically the same as explained in connection with the rear or follower engaging key 16^a. Obviously the collars 24 will act to prevent longitudinal shifting of the keys so that they must remain in proper position with the offset portion engaged through the slot in the coupler shank or follower, as the case may be. Clearly the collars cannot become displaced until the securing members 28 are removed and the intermediate sections 18 of the keys withdrawn, a positive interlock being thus attained.

When both keys have been placed in position as above described and as illustrated, it is apparent that the follower and coupler will have been advanced so as to be capable of having normal travel. As the yoke is not advanced it is true that there will be an increase in the length of the draft gear pocket defined between the follower and the rear end of the yoke. It is, however, a simple matter to restore this pocket to normal dimensions by interposing shims or the like at the rear of the front follower or possibly at some other point to compensate for the distance which the front follower has been moved forwardly by the employment of the keys.

As the result of employing replacement keys constructed in accordance with this in-

vention it is evident that couplers may be used for a much greater length of time than is ordinarily possible, there being consequently a material saving in the cost of maintenance.

While I have shown and described the preferred embodiment of the invention and certain specific structure, it should be understood that the disclosure is merely illustrative of the principle involved and that the right is reserved to make all such changes or modifications in the detailed features as will not depart from the spirit of the invention or the scope of the claims hereunto appended.

Having thus described the invention, I claim:

1. In a draft rigging including slotted elements, a key passing through the slots for connecting the elements, the key being formed with an offset intermediate portion received within the slot in one element for advancing said element with respect to the other.

2. In a draft rigging including slotted elements, a key passing through the slots for connecting the elements formed with an offset intermediate portion engageable with the side of the slot in one element for shifting the position thereof with respect to the other element, the key being formed of a plurality of detachably connected sections.

3. In a draft rigging including a slotted coupler shank and slotted yoke, a key passing through the slots for connecting the shank and yoke formed with an offset intermediate portion for advancing the coupler with respect to the yoke, the key being formed of a plurality of detachably connected sections having interlocking means.

4. In a draft rigging including cheek plates, a yoke and a coupler, all provided with slots, a draft key extending through the slots and having means engaging within the slot in the coupler shank for advancing the position of the coupler.

5. In a draft rigging including cheek plates, a yoke and a coupler, all formed with slots, the combination of a draft key extending through the slots and having a forwardly offset intermediate portion engaging within the slot in the coupler shank for advancing the coupler.

6. In a draft rigging including cheek plates, a yoke and a coupler, all formed with slots, the combination of a draft key extending through the slots and having a forwardly offset intermediate portion engaging within the slot in the coupler shank for advancing the coupler, the width of the key at said offset portion corresponding to its width at the end portions.

7. In a draft rigging including cheek plates, a yoke and a coupler, all formed with slots, the combination of a draft key extend-

ing through the slots and having a forwardly offset intermediate portion engaging within the slot in the coupler shank for advancing the coupler, the width of the key at said offset portion corresponding to its width at the end portions and according with standard equipment.

8. In a draft rigging including cheek plates, a yoke and a coupler, all formed with slots, the combination of a draft key extending through the slots and having a forwardly offset intermediate portion engaging within the slot in the coupler shank for advancing the coupler, the width of the key at said offset portion corresponding to its width at the end portions, the key including a plurality of sections detachably connected, means on the key cooperating with the cheek plates for preventing longitudinal movement of the key.

9. In a draft rigging including cheek plates, a yoke and a coupler, all formed with slots, the combination of a draft key extending through the slots and having a forwardly offset intermediate portion engaging within the slot in the coupler shank for advancing the coupler, the width of the key at said offset portion corresponding to its width at the end portions, the key including a plurality of sections detachably connected, means on the key cooperating with the cheek plates for preventing longitudinal movement of the key, and means for locking the sections together.

10. In a draft rigging including cheek plates, a yoke and a coupler, all formed with slots, the combination of a draft key extending through the slots and having a forwardly offset intermediate portion engaging within the slot in the coupler shank for advancing the coupler, the key including forward and rear sections formed respectively with an extension and a depressed portion.

11. In a draft rigging including cheek plates, a yoke and a coupler, all formed with slots, the combination of a draft key extending through the slots and having a forwardly offset intermediate portion engaging within the slot in the coupler shank for advancing the coupler, the key including forward and rear sections formed respectively with an extension and a depressed portion, and an intermediate section disposed between the forward and rear sections and detachably connected therewith.

12. In a draft rigging including cheek plates, a yoke and a coupler, all formed with slots, the combination of a draft key extending through the slots and having a forwardly offset intermediate portion engaging within the slot in the coupler shank for advancing the coupler, the key including forward and rear sections formed respectively with an extension and a recess, an intermediate section disposed between the forward

and rear sections, and means embracing the sections for preventing relative lateral movement thereof.

13. In a draft rigging including cheek plates, a yoke and a coupler, all formed with slots, the combination of a draft key extending through the slots and having a forwardly offset intermediate portion engaging within the slot in the coupler shank for advancing the coupler, the key including forward and rear sections formed respectively with an extension and a recess, an intermediate section disposed between the forward and rear sections, means embracing the sections for preventing relative lateral movement thereof, and means engaging the sections for preventing relative longitudinal movement thereof.

14. In a draft rigging including cheek plates, a yoke and a coupler, all formed with slots, the combination of a draft key extending through the slots and having a forwardly offset intermediate portion engaging within the slot in the coupler shank for advancing the coupler, the key including outer sections and an intermediate section, means embracing the assembled sections for preventing relative lateral movement thereof and longitudinal displacement of the assembled key.

15. In a draft rigging including cheek plates, a yoke and a coupler, all formed with slots, the combination of a draft key extending through the slots and having a forwardly offset intermediate portion engaging within the slot in the coupler shank for advancing the coupler, the key including outer sections and an intermediate section, means

embracing the assembled sections for preventing relative lateral movement thereof and longitudinal displacement of the assembled key, said means being formed as a collar, the outer sections having their outer edges grooved for the accommodation of the collar.

16. In a draft rigging including cheek plates, a yoke and a coupler, all formed with slots, the combination of a draft key extending through the slots and having a forwardly offset intermediate portion engaging within the slot in the coupler shank for advancing the coupler, the key including outer sections and an intermediate section, means for preventing relative lateral movement of the sections, the confronting faces of the sections being formed with mating notches, and securing elements passing through the notches for preventing relative longitudinal movement of the sections.

17. Means for connecting a horizontal yoke with the coupler of a draft rigging, the coupler shank and yoke being formed with slots, comprising a key provided intermediate its ends with a forwardly extending projection engageable with the forward end of the slot in the coupler shank for advancing the coupler with respect to the yoke.

18. In combination with a coupler shank and yoke, both formed with slots, a connecting key extending through the slots and provided intermediate its ends with means cooperating with the slot in the coupler shank for advancing the same with respect to the yoke.

In testimony whereof I affix my signature.

SIGVARD SIMONSON.
